DESIGN FOR A HANDLE FOR A LAWN MOWER

Earl L. Schofield, Auburn, Ind., assignor to The
Atwood Vacuum Machine Company, Rockford,
Ill., a copartnership composed of Seth B.
Atwood and James T. Atwood

Application May 26, 1943, Serial No. 110,303

Term of patent 14 years

(Cl. D40—1)

To all whom it may concern:

Be it known that I, Earl L. Schofield, a citizen
of the United States, residing at Auburn, in the
county of De Kalb and State of Indiana, have in-
vented a new, original, and ornamental Design for
a Handle for a Lawn Mower, of which the follow-
ing is a specification, reference being had to the
accompanying drawing forming part thereof.

In the drawing:

Fig. 1 is a front elevational view of a handle for
a lawn mower, showing my new design; and
Fig. 2 is a side elevational view thereof.

I claim:

The ornamental design for a handle for a lawn
mower, substantially as shown.

EARL L. SCHOFIELD.
